UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

COMPRESSOR.

Application filed April 9, 1927. Serial No. 182,449.

This invention pertains to fluid compressors, and more particularly to controlling mechanisms for compressors of the gasoline engine driven type.

5 An object of this invention is to provide an improved compressor controlling mechanism. Another object is to provide an improved controlling mechanism for a gasoline driven compressor whereby the latter may be automatically unloaded when the driving engine is initially started, the improved controlling mechanism being associated with the usual constant speed governor for the engine. Another object is to provide an improved compressor unloading mechanism associated with the constant speed governor for the compressor driving engine and having combined therewith automatic means for controlling unloading operated by the variations in receiver pressure. A more specific object of this invention is to provide improved automatic controlling mechanism for a gasoline driven compressor whereby the speed of the engine automatically controls the engine 10 throttle and the loading and unloading of the compressor, this controlling mechanism further comprising receiver pressure controlled unloading mechanism for the compressor. Still another object is to provide an improved 15 automatic unloading mechanism for a gasoline driven compressor whereby the engine may be started up under no load and the compressor may be automatically loaded when the engine comes up to speed. Yet another 20 object is to provide an improved compressor controlling mechanism of an exceedingly simple and inexpensive character which may be applied to a standard compressor with a minimum of change. These and other objects and advantages of this invention will, however, hereinafter more fully appear.

In the accompanying drawing there is shown for purposes of illustration one form which the invention may assume in practice.

45 In this drawing,—

Fig. 1 is a side elevational view of a gasoline driven compressor of the portable type in which my improved controlling mechanism is incorporated.

50 Fig. 2 is a detail view partially in section, illustrating the improved controlling mechanism per se.

Fig. 3 is a detail sectional view illustrating

one of the inlet valve unloading mechanisms for the compressor.

Fig. 4 is a detail sectional view taken through the throttle for the gasoline driving engine.

The portable compressor outfit 1 includes a gasoline motor 2 and a compressor 3. The 60 motor is provided with any suitable type of constant speed governor 4. From one end of the governor extends a cylindrical extension 5 slotted on one side; and within this extension is disposed a rod 6 actuated in the customary way by the governor 4, that is to say, if the speed increases, the rod 6 is shoved to the right and if the speed decreases, the rod 6 is drawn to the left. Through the above mentioned slot extends a connection 7, actuated from the rod 6, for controlling the supply of combustible gases to the motor. Secured to the end of the extension 5 is a casing 8 within which is disposed a valve 9 of the spool type. A stem 10 extending from the valve 9 is held in abutting relation with the end of rod 6 by a suitable spring 26 disposed in the opposite end of the valve casing. The annular groove 11 of the spool valve is shown in Fig. 2 as connecting a vent 20 with a port 12 in the valve casing. One end of the spool valve is shown as covering a port 13. The valve casing at the end opposite the cylindrical extension 5 is provided with a vent 14. A pressure fluid line 15 extends between the port 12 and mechanism for unloading the compressor. This unloading mechanism may comprise a servo-motor to which compressed air or other actuating medium is supplied. The embodiment shown in Fig. 3 is 90 of a well known construction; and includes a piston-like member slidable in a cylinder 23 which receives pressure fluid from the line 15. The piston-like member carries fingers 22 which are adapted to engage the inlet valve 24 of the valve mechanism 25 for the compressor cylinder. When the fingers 22 engage the inlet valve 24 and force it off its seat, the compressor runs unloaded.

Between the port 13 and the air receiver 19 extends a line 17. Between the lines 15 and 17 extends a bypass 18 which is controlled by a conventional pop valve 21. Such a pop valve is adapted to be unseated when the pressure in line 17 exceeds a predetermined amount, and to be returned to seating posi-

tion again when the pressure falls somewhat below that amount.

Before describing the operation, a review should be had of the difficulties which have 5 been overcome. A gasoline motor has poor efficiency in starting and therefore should not be required to start up under a heavy load. I have so designed my improved unloading mechanism that the compressor is always un- 10 loaded when the motor is not running and is not loaded until the motor has attained its running speed. Furthermore, to obtain the best efficiency, the delivery of air to the receiver should cease when the maximum pressure which the receiver is designed to take has 15 been reached. I have provided an arrangement for unloading the compressor when such a pressure is reached in the receiver.

Coming now to the operation of the mechanism, suppose that the operator has shut off 20 the motor. As it comes to a stop, the rod 6 is moved to the left, thereby allowing the spool valve 9 to assume such a position that the vent 20 is closed and the lines 17 and 15 are placed 25 in communication by way of the annular groove 11. Pressure fluid therefore passes from the receiver through lines 17 and 15 and actuates the unloading mechanisms 16. Since 30 the preceding takes place whenever the motor is stopped, the compressor is always un- loaded when starting up.

The operation of the device during starting 35 of the compressor is easily understood. The governor 4 responds to the increasing speed of the motor 2 and gradually moves the rod 6 to the right. The spool valve 9 approaches the position shown in Fig. 2. The position of vent 20 has been so selected that it is not uncovered until the motor has reached its running speed. When vent 20 is uncovered, it is 40 obvious from Fig. 2 that port 18 is closed; the groove 11 is therefore in communication with vent 20 and line 15 only; and the unloading mechanisms 16 are vented to the atmosphere. This allows the valves 24 to resume their 45 function of controlling the inlets to the compressor, and the compressor is therefore loaded.

In conjunction with the unloading mechanism just described there has been provided 50 the bypass 18 controlled by the pop valve 21. Should the pressure in receiver 19 pass a pre- determined pressure (which should not be higher than the rated capacity of said receiver), the pop valve 21 will allow pressure fluid to pass from line 17 through the bypass 18 to line 15, and the unloaded mechanisms 16 are actuated. When the pressure in receiver 19 has fallen somewhat below the pop-off pressure, the valve 21 is again seated. During this 55 period of unloading there has been a leakage through the vent 20, but this is so small as not to affect the operation of the unloading mechanisms 16. When the pop valve 21 reseats, 60 however, the pressure fluid in line 15 leaks out

through vent 20 to the atmosphere and the compressor is again loaded. The pop valve automatically takes care of variations in receiver pressure, whereas the valve 9 insures that the compressor be unloaded whenever the 70 motor is started up.

While I have in this application specifically described one form which my invention may assume in practice, it will be understood that this form of the same is shown for purposes 75 of illustration and that the invention may be modified and embodied in various other forms without departing from its spirit or the scope of the appended claims.

What I claim as new and desire to secure by 80 Letters Patent is:

1. In a compressor controlling mechanism, a driving engine having a throttle, a governor for said throttle controlled by the speed of said engine, a fluid compressor driven by said engine, an unloading device for said compressor, a control for said unloading device operated by said engine throttle governor, and a second control for said unloading device responsive to the compressor discharge pressure, said second mentioned control being independent of the engine throttle governor. 85 90

2. In a compressor controlling mechanism, a driving engine having a throttle, a governor for said throttle controlled by the speed of said engine, a fluid compressor driven by said engine, a pressure fluid operated unloading device for said compressor, a control for said unloading device operated by said engine throttle governor and, a second control for 95 100 said unloading device responsive to the compressor discharge pressure, both of said controls cooperating with a common fluid passage leading to the unloading device.

3. In a compressor controlling mechanism, 105 a driving engine having a throttle, a governor for said throttle controlled by the speed of said engine, a fluid compressor driven by said engine, an unloading device for said compressor, mechanism controlled by said speed controlled throttle governor for automatically operating said unloading device to unload said compressor when the engine is stopped and for automatically loading said compressor when the engine comes up to speed, said mechanism including means for alternatively admitting pressure fluid to said unloading device and for venting the latter to atmosphere, and mechanism responsive to the compressor discharge pressure for operating said unloading device to unload said compressor when said discharge pressure reaches a predetermined maximum, said vent means being common to both said speed controlled unloading mechanism and said compressor discharge pressure controlled unloading mechanism. 110 120 125

4. In a compressor controlling mechanism, a driving engine, a compressor driven thereby, a constant speed governor for said engine, an unloading device for said compressor, 130

- mechanism controlled by said speed governor for operating said unloading device, and mechanism controlled by compressor discharge pressure independently of said speed 5 governor for operating said unloading device to unload said compressor when the compressor discharge pressure reaches a predetermined maximum.
5. In combination, a prime mover, a constant speed governor therefor, a compressor driven by said prime mover, unloading mechanism for the compressor including a valve controlled by the constant speed governor, a passage controlled by said valve, a source 10 of pressure fluid being connected to one end of said passage, and a servo motor for the unloading mechanism at the other end.
6. In combination, a prime mover, a constant speed governor therefor, a compressor 15 driven by said prime mover, pressure fluid actuated means for unloading said compressor, and a spool valve for controlling flow of fluid to said unloading means, said spool valve being reciprocated under control 20 of said governor.
7. In combination, a prime mover, a constant speed governor therefor, a compressor driven by said prime mover, a receiver, unloading means for said compressor including 25 a servo motor for actuating the unloading mechanism, means providing a passage for conducting pressure fluid from said receiver to said servo motor, and a pair of valves controlling the flow of fluid through said passage, one of said valves being actuated by 30 said governor and the other being responsive to fluid pressure in said receiver.
8. In combination, a prime mover, controlling means therefor including a throttle 35 and a constant speed governor for regulating said throttle, a compressor driven by said prime mover, and unloading mechanism for said compressor having a pair of controls one of said controls being actuated by said prime 40 mover controlling means and the other of
- said controls being actuated in response to compressor discharge pressure independently of said prime mover controlling means.
9. In combination, a prime mover, controlling means therefor including a throttle 50 and a constant speed governor for regulating said throttle, a compressor driven by said prime mover, unloading mechanism for said compressor including a servo-motor, and a pair of controls for the medium supplied to 55 said servo-motor for actuating the same, one of said controls being actuated by said prime mover controlling means and the other of said controls being actuated in response to compressor discharge pressure independently 60 of said prime mover controlling means.
10. In combination, a prime mover, a constant speed governor therefor, a compressor driven by said prime mover, and unloading mechanism for said compressor including a servo-motor for actuating the same and means controlled by said constant speed governor for conducting actuating medium to said servo-motor.
11. In combination, a prime mover, a constant speed governor therefor, a compressor driven by said prime mover, an unloading device for said compressor, and mechanism controlled by said constant speed governor for controlling said unloading device to maintain said compressor unloaded until the prime 70 mover comes up to speed.
12. In combination, a prime mover, a constant speed governor therefor, a compressor driven by said prime mover, an air receiver 75 for said compressor, a fluid actuated unloading device for said compressor, and mechanism controlled by said constant speed governor for admitting air from said receiver to said unloading device to effect unloading of said compressor until said prime mover comes up to speed.

In testimony whereof I affix my signature.

CHARLES F. OSGOOD.
